SLOT BUNKER

Heinz Brahmsepe, Essen-Steele, Germany, assignor, by
mesne assignments, to Koppers Company, Inc., Pitts-
burgh, Pa., a corporation of Delaware

Application February 25, 1954, Serial No. 412,526

4 Claims. (Cl. 214—17)

A type of slot bunker is known, with a central saddle and material stored on both sides of it, in which the material is removed through a slot arranged below the centre and on both sides of the saddle by means of scissors-shaped emptying arms coupled with one another, which act simultaneously on both surfaces of the slot.

A slot bunker formed in this way has the advantage that, by the arrangement of two bunkers, that is of a bunker arranged on each side of the saddle, the material can be removed in an adjustable mixing ratio on to a conveyor arranged underneath the slot of the bunker.

With the known types of slot bunker there are arranged on the emptying trucks which move underneath the slot bunker two pairs of emptying arms, of which the one pushes the material away from the supporting surfaces on the forward movement and the other on the backward movement. At each end of the bunker these emptying arms are linked by means of sloping surfaces arranged on the bunker in such a way that the one pair of emptying arms comes into the position of rest and the other into the working position.

The present invention relates to a further development of the slot bunker constructed according to the main patent, consisting substantially in a simplification of the arrangement of the emptying arms.

According to the invention the emptying arms are carried on the emptying truck so that they swing on a hinge and are provided in both directions of movement with emptying arms which engage on both supporting surfaces.

By such a construction of the emptying arms according to the invention only one pair of pivoted emptying arms is necessary, these emptying arms being constructed substantially the same in both directions. Thereby the result is attained that the change-over of the emptying arms at each end of the slot bunker results automatically, on the reversal of the direction of travel the emptying truck, the emptying arm previously supported in the working position automatically coming into the position of rest out of the region of the material owing to the resistance of the material, and at the same time the arm arranged to lie out of the path of material in the other direction of travel automatically engaging in the material piled up on the supporting surfaces and coming into the final working position.

A further characteristic of the invention is the arrangement on the emptying truck, between the emptying arms when they are in the position of rest, of adjusting members for the adjustment of the other emptying arms when they are in the working position with respect to the amount of material to be removed. Thereby the adjustment of the emptying arms can be made separately for each emptying arm in accordance with the desired mixing ratio of the material.

Preferably the adjusting members according to the invention are formed tapering conically and so arranged that the narrower portion of their conical taper is able to swing between the emptying arms which are in the position of rest. The adjusting members each lie on a shaft

2

provided with an actuation lever on the side of the emptying truck, so that they can be easily operated.

An object of the invention is further to connect the cable, which moves the emptying truck, with the ends of the emptying truck through two rollers arranged at each end. Thereby the cable runs from these rollers over a cable drum which is connected with the drive, and over upper and lower guiding rollers arranged for each of the two rollers of the emptying truck.

10 Such an arrangement of the cable avoids tipping of the emptying truck, as with too much length in one side the cable can equalise itself on the two rollers arranged on the emptying truck.

Finally it is also an object of the invention to arrange 15 between the cable drum and the vertically arranged direction changing rollers a horizontally displaceable guiding roller. Thereby the guiding rollers can adapt themselves in accordance with the length of the cable, which shifts in a horizontal plane and leads to the direction 20 changing rollers and is wound several times round the cable drums, without coming off the rollers.

The invention is shown in the diagrams in a preferred constructional form.

Fig. 1 shows the lower part of a slot bunker formed 25 according to the invention, in vertical section on the lines I—I of Fig. 2;

Fig. 2 is a plan of the emptying truck;

Fig. 3 shows the adjusting member which adjusts the emptying arms, in a vertical section on the lines III—III 30 of Fig. 2;

Fig. 4 shows diagrammatically the cable which moves the emptying truck, in side view, and

Fig. 5 in plan.

The slot bunker, provided with a saddle 1, consists of 35 the two sections 2 and 3, which are separated from one another by a vertical separating wall, not shown in the diagram, arranged above the saddle 1. Underneath each bunker section 2, 3 is arranged along the slot bunker a supporting surface 4 on which the material is supported 40 in accordance with a piling angle 5. The distance of the lower end of the piling angle to the end of the supporting surface 4 can be adjusted by means of adjustable walls 6.

Between the two supporting surfaces 4 is formed a longitudinal 45 through slot 7, through which the material is transferred on to a conveyor belt 8 arranged below.

On a concrete base 9 there is carried on rails 10 an emptying truck 12, which can move along the slot 7 by means of running wheels 11, and which has guiding walls 50 13 reaching to the neighbourhood of the conveyor belt 8. Fixed on a cross girder 14 of the emptying truck 12 is a vertical pin 15. On the upper end of the pin portions of cylinders 16 are carried rotatably. Fixed to these portions of cylinders 16 are arms 17, 18 which are provided 55 with vertical shovel surfaces 19.

As is seen from Fig. 2, the two arms 17, 18 are disposed in the form of an obtuse angle so that when the arms 17 are in the position of rest in alignment with slot 60 7 the arms 18 engage on the supporting surfaces 4. In this position the transport device of the emptying truck 12 runs in the direction of the arrow 20. Thereby the arms 18 engage in the material formed at the piling angle so that by the resulting resistance the arms 18 always lie 65 in the same working position and the arms 17 always remain in the same position of rest.

When the emptying truck 12 reaches the end of the bunker and the direction of movement is then reversed, the resistance of the piled-up material causes a swinging of the arms 18 round the vertical pin 15, whereby the arms 17 come into the working position and swing out fully

on engaging in the piled-up material thereby rotating arms 18 into alignment with slot 7.

At the ends of the emptying truck 12 conical adjusting members 21, are pivotally mounted so that they in unison can swing round a shaft 22. The adjusting members 21 first enter at the narrower portion of their conically tapering ends, between the emptying arms 17, 18 which are in the position of rest, for example when in the direction of movement shown in Fig. 2, the emptying arms 17. The shaft 22 is provided with a lever 23 which is adjustable by means of stop pins 24, by means of which the adjusting member 21 can be turned toward and as far between the two emptying arms as corresponds to the position of the other of those emptying arms, which are doing the emptying, that may be desired with respect to the amount of material to be removed. The mixing ratio of the various kinds of material stored in the bunkers 2 and 3 thereby results in conjunction with adjustment of the slider valve 6 of one of the two bunker sections. The emptying arm engaging on the opposite supporting surface can however also be adjusted differently, for example by having the two conically tapered side walls 25 each being independently adjustable.

The two arms 17, 18 can also be formed so that if necessary one of the arms can be cut out of action.

The emptying arms 17, 18 can travel through a limited region of the bunker, with automatic change-over, without having to go all the way to the ends of the bunker, merely by reversal of the direction of travel of the driving motor. Thus by sub-dividing the bunker longitudinally into bunker sections with different sorts of material, particular sections of the length can be travelled with a single emptying truck.

As is seen from Figs. 4 and 5, the emptying truck is driven by means of a cable 26 which runs over the rollers 27 arranged on both sides at the ends of the emptying truck 12. The cable 26 also runs over direction-changing rollers 28 arranged at the one end, over direction changing rollers 29 arranged at the other end, guiding rollers 30 carried above, and cable drums 31. The cable drums 31 are connected with a drive 32 through a continuously variable gear 33 and a gear drive 34.

The cable is wound several times over the cable drums 31 which are arranged on both sides of a common shaft 35. Thereby the ends of the cable going away from the cable drums run off each in a different vertical plane.

The guiding rollers 30 are carried axially displaceable on a shaft 36, so that the rollers 30 can follow the horizontal movement of the cable without any danger of the cable jumping off the roller. By the arrangement of the guiding rollers 30 above the cable drums 31 the guiding rollers lie at such a distance from the direction changing rollers 29 that there is no danger of the cable wandering away from the rollers, which are on fixed bearings.

What I claim is:

1. Slot bunker with a central saddle and material supporting surfaces on opposite sides of it, a slot between each supporting surface and the saddle, an emptying truck movable along the saddle below the same and having two pivoted pairs of emptying arms carried by the emptying truck in position for one arm of each pair of arms to

engage through the slots in position over the material supporting surfaces on opposite sides of the saddle to remove material therefrom to beneath the saddle while the other arm of each pair of arms lies under the saddle in one direction of movement of the emptying truck along the saddle, and said other arm of each pair likewise engages through the slots over said opposite side material supporting surfaces while said one arm of each pair lies under the saddle in the opposite direction of movement under the saddle, said arms of each pair being disposed in the form of an obtuse angle and the two pairs being pivotally mounted one above the other on a common axis whereby the arms of the pairs are automatically reversed in position by the material on the supporting surface on change in direction of movement of the emptying truck under the saddle, and a conical adjusting member at each end of the pivoted pairs and carried by a horizontal pivotal shaft mounted on the emptying truck in position for interposition between one arm of each of the pivoted pairs when they lie together beneath the saddle out of engagement with the supporting surfaces on opposite sides of the saddle.

2. Slot bunker as claimed in claim 1, and further characterized by the conical adjusting member being regulable by means of a lever on the horizontal pivotal shaft at the outer sides of the emptying truck.

3. Slot bunker with a central saddle and material supporting surfaces on opposite sides of it, a slot between each supporting surface and the saddle, an emptying truck movable along the saddle below the same and having two pivoted pairs of emptying arms carried by the emptying truck in position for one arm of each pair of arms to engage through the slots in position over the material supporting surfaces on opposite sides of the saddle to remove material therefrom to beneath the saddle while the other arm of each pair of arms lies under the saddle in one direction of movement of the emptying truck along the saddle, and said other arm of each pair likewise engages through the slots over said opposite side material supporting surfaces while said one arm of each pair lies under the saddle in the opposite direction of movement under the saddle, said arms of each pair being disposed in the form of an obtuse angle and the two pairs being pivotally mounted one above the other on a common axis whereby the arms of the pairs are automatically reversed in position by the material on the supporting surface on change in direction of movement of the emptying truck under the saddle, and a cable to produce the movement of the truck, said cable being connected with the two opposite ends of the truck over two rollers arranged at each of said two ends thereof and over a cable drum through upper and lower pairs of rollers for each pair of rollers at each end of the truck.

4. Slot bunker as claimed in claim 3, and further characterized by one pair of upper and lower pairs of rollers being axially displaceable on a shaft for the pair.
